UNITED STATES PATENT OFFICE.

JAMES H. VAN DORN, OF CLEVELAND, OHIO.

WROUGHT-METAL JOIST-HANGER.

SPECIFICATION forming part of Letters Patent No. 537,505, dated April 16, 1895.

Application filed November 28, 1894. Serial No. 629,972. (No model.)

To all whom it may concern:

Be it known that I, JAMES H. VAN DORN, a citizen of the United States, residing at Cleveland, in the county of Cuyahoga and State 5 of Ohio, have invented certain new and useful Improvements in Wrought-Metal Joist-Hangers; and I do hereby declare the following to be a full, clear, and exact description of the invention, such as will enable others skilled in 10 the art to which it appertains to make and use the same.

My invention relates to wrought metal joist hangers; and the object of the invention is to produce a wrought metal joist hanger which 15 shall be strong enough for the intended use, and, in my opinion, stronger than any metal joist hanger heretofore made of equal weight, and which shall also be cheaper than any wrought metal joist hanger heretofore made. 20 The invention consists of the described hanger, the blank from which it is made, and the method of forming said blanks with no considerable waste of material.

In the drawings, Figures 1 and 2 are perspective views of two forms of bars from which the hanger blanks may be cut alternately from opposite sides. Figs. 3 and 4 are end views of the bars shown in Figs. 1 and 2 respectively; and Fig. 5 is a perspective view 30 of the completed hanger.

Referring to the parts by letter, A A represent the two substantially parallel vertical sides of the hanger; B, the intermediate horizontal shelf; and C C represent flanges which 35 are integral with the rear edges of the two sides and lie at right angles thereto. These flanges extend beyond the ends of the sides and are bent backward into planes substantially at right angles to the sides themselves 40 and parallel to the shelf B, thereby forming arms C' C' which are adapted to lie on top of and to be secured to the beam by which the hanger is to be supported. Holes are formed in the flanges C C and in the arms C' C', 45 through which pass the screws or spikes by means of which the hanger may be secured to said beam. In the preferred form, which is shown in the drawings, there is no flange on the rear edge of the shelf. 50 In forming the hanger the rear part of that part of the blank which forms the shelf is cut

off, whereby the bending of the flanges on the sides into the desired position may be effected without danger that the blank will be split during said bending operation.

When the hanger is secured to the beam, the flanges C C lie against the side of the beam, and the arms C' C' lie on top thereof; and when the hanger is fastened in this position by screws or nails passing through said 60 sides and arms, it is believed that the hanger has greater supporting strength than any hanger ever made of equal weight.

By supporting the hanger in part by the side flanges, there is less danger than there 65 would otherwise be that the arms C' C' will straighten out wholly or in part and thus permit the hanger to be pulled loose from the beam. Another advantage of the connection of the hanger to the beam by means of the 70 side flanges, is that thereby all side motion of the hangers is prevented; and through the described hangers, a joist may be secured to a beam as firmly as if mortised thereto.

The described hanger may be made by cutting blanks alternately from opposite sides of either of the two forms of bars shown in Fig. 1 or 2. Fig. 1 shows a flat bar, and when the blanks (which have oppositely inclined ends and unequal parallel sides) are cut from this 80 bar, the sides thereof remain connected to and projecting from the ends of the long sides,—forming the arms C' C'; and that part C² of the said edge which is at the middle of the blank and attached to that part thereof 85 from which the shelf is formed, is cut away, as indicated in Figs. 1 and 2. When the blank has been cut out, the rear side is bent at right angles to the body, thereby forming the flanges C C and arms C' C'; the body is 90 bent on dotted lines 1—2 to form the sides and intermediate shelf; and the arms are bent back on lines 3—4, thus completing the hangers.

The bar shown in Fig. 2 is rolled with the 95 two edge flanges at right angles to the body or web. The blanks are cut out in the manner heretofore described; and the part C² of the flange is cut off from that part of the blank which forms the shelf. When this 100 form of bar is used, the operation of turning the flanges at right angles to the body of the

blank is of course dispensed with, or rather, said bending is done before the blanks are cut out.

It is advantageous to employ a bar having 5 its sides a little thicker than the web, because thereby the hanger will be stronger.

Having described my invention, I claim—

1. The herein described process of making blanks for joist hangers, which consists in 10 cutting sections alternately from opposite sides of a wrought metal bar, cutting the edges of said bar away from the opposite sides of adjacent sections, and leaving the edges so cut away from each section attached to and 15 projecting from the ends of the adjacent sections, substantially as and for the purpose specified.

2. The herein described process of making blanks for joist hangers, which consists in 20 cutting, alternately, from opposite sides of a wrought metal bar, sections each of which has oppositely inclined ends and unequal paral-

lel sides and arms projecting from both ends of its longer side, substantially as and for the purpose specified.

3. The herein described process of forming 25 a wrought metal joist hanger, which consists in cutting alternately from opposite sides of a bar, blanks having oppositely inclined ends and unequal parallel sides, and arms which project from both ends of the long side, turning the edge of the long side up at right angles to the body, cutting away the middle part C² of said turned up edge, bending the blank 30 to form two parallel sides and an intermediate shelf, and bending back the projecting arms, substantially as and for the purpose specified.

In testimony whereof I affix my signature in presence of two witnesses.

J. H. VAN DORN.
